UNITED STATES PATENT OFFICE.

IRA H. FREESE, OF CLARKSBURG, WEST VIRGINIA, ASSIGNOR TO HAZEL-ATLAS GLASS CO., OF WHEELING, WEST VIRGINIA, A CORPORATION OF WEST VIRGINIA.

DESIGN FOR A TUMBLER.

Application filed December 6, 1928. Serial No. 29,134. Term of patent 7 years.

To all whom it may concern:

Be it known that I, IRA H. FREESE, a citizen of the United States, residing at Clarksburg, in the county of Harrison and State of West Virginia, have invented a new, original, and ornamental Design for Tumbler, of which the following is a specification, reference being had to the accompanying drawing, forming part thereof.

Figure 1 is a perspective view of a tumbler; and

Figure 2 is a horizontal sectional view of a tumbler, taken on line 2—2 of Figure 1, showing my new design.

I claim:

The ornamental design for a tumbler, as shown.

IRA H. FREESE.
